UNITED STATES PATENT OFFICE.

MORRIS KAPLAN, OF NEW YORK, N. Y.

EYEGLASSES.

1,212,776.

Specification of Letters Patent. Patented Jan. 16, 1917.

Application filed April 22, 1916. Serial No. 92,872.

To all whom it may concern:

Be it known that I, MORRIS KAPLAN, a citizen of the United States, residing at New York, in the county of New York and State of New York, have invented new and useful Improvements in Eye-glasses, of which the following is a specification.

This invention relates essentially to the method of mounting the lenses of an eye-glass, the fundamental object being to securely clamp the lenses in fixed relation to the mounting.

The invention is designed to provide readily accessible auxiliary devices for fastening the lens to the mounting when the pivotal connection between the lens and strap of the mounting becomes loose.

It is well known that if the pivotal connection for holding the lens to the strap becomes loose the lens will shift relative to the pivot, then if any sudden shock is given to the lens it will break; or if the pivot is fastened too tight the strap will have a tendency to fracture the lens.

The novel features of the invention are more fully described in the following specification and claims and illustrated in the accompanying drawing in which:

Figure 1 represents a front elevation of an eye-glass embodying this invention. Fig. 2 is a similar view of a portion of the eye-glass on a larger scale. Fig. 3 is a perspective view of a clamping device.

In this drawing is shown an eye-glass provided with a pair of lenses *a* having straps or clamps *b* embracing the lens. Screws *c* extend through a hole in each lens and engage the straps for mounting the lens. The strap is provided with an extension *d* projecting from the upper portion of the strap and made to engage the rim or perimeter of the lens. To the inner ends of each strap is fixed a spring bridge *e* and a nose guard *f*.

A detent or shoe *g* is pivoted at *h* to the lower portion of the strap. This detent has a wedge or cam shaped portion *i* the object of which will be hereinafter described.

Fixed to the lower portion of the strap is a post *j* having screw threaded upper end for engagement with a nut *k* and a washer *m* mounted on the post. The upper portion of the post is split so that it can be spread by a tool to get better engagement of the thread with the bore of the nut. The clamping device for locking the detent includes a

pair of bifurcated arms *n* for coaction with the surface of the lens. These arms straddle the detent and the rear wall or crotch of the bifurcation will coöperate with the wedge portion of the detent. The tail end of the clamp has an aperture for slidingly mounting the device on the post. Springs *q* coacting with the upper and lower parts of the tail end of the clamp will serve as cushions to take up any sudden jar given to the lens.

When it is desired to tighten the lens to the mounting the nut is manipulated to move toward the axis of the lens, thus compressing the springs and hence moving the clamp upwardly. The crotch of the clamp will ride up the wedge or incline moving the free end of the detent to engage with the rim of the lens. In this arrangement the detent will hold the lens firmly against the upper extension although the screw *c* can be loose. The arms of the clamp by closely embracing the surface of the lens, will obviate wobble of the lens and consequent breakage of the same is avoided.

I claim:

1. In an eye-glass the combination with a lens mounting having a strap to engage the rim of the lens, of a vibratory device carried by the mounting for engagement with another portion of the rim of the lens, and means coöperating with the device to force it against the rim of the lens.

2. In an eye-glass the combination with a lens mounting having a strap to engage the rim of the lens, of a detent pivoted to the mounting for engagement with another portion of the rim of the lens, and means on the mounting for forcing the detent against the rim of the lens.

3. In an eye-glass the combination with a lens mounting having a strap to engage the rim of the lens, of a detent pivoted to the mounting for engagement with another portion of the rim of the lens, and a clamp coacting with the detent for forcing it against the rim of the lens.

4. In an eye-glass the combination with a lens mounting having a strap to engage the rim of the lens, of a detent pivoted to the mounting for engagement with another portion of the rim of the lens, and a bifurcated clamp to coact with the detent to hold the lens in fixed relation with the mounting.

5. In an eye-glass the combination with a

lens mounting having a strap to engage the rim of the lens, of a wedge shaped detent pivoted to the mounting, for engagement with another portion of the rim of the lens,

5 and a clamp coating with the wedge for holding the lens in fixed relation to the mounting.

6. In an eye-glass the combination with a lens mounting having a strap to engage the 10 rim of the lens, of a wedge-shaped detent pivoted to the mounting for engagement with another portion of the rim of the lens, a

clamp coating with the wedge for holding the lens in fixed relation to the mounting, and means for adjusting the clamp to lock 15 the detent.

In testimony whereof I have hereunto set my hand in the presence of two subscribing witnesses.

MORRIS KAPLAN.
